UNITED STATES PATENT OFFICE

2,290,044

TIMING MECHANISM

Walter J. Haag, Dayton, Ohio, assignor to The Brownell Company, Dayton, Ohio, a corporation of Ohio

Application April 25, 1940, Serial No. 331,618

9 Claims. (Cl. 200—30)

This invention relates to timing mechanism and this application is a division of my co-pending application, Serial Number 284,564, filed July 14, 1939, for Intermittent stroke control for ram-feed stokers.

The present invention has particular application to apparatus wherein the operation of certain parts have a sequential or timed relation to the operation of certain other parts, and has for a particular object the provision of timing mechanism for this purpose, having control means for readily altering or changing the timed relation of the operation of parts of the apparatus to which the invention is applied.

A further object of the invention is to provide timing mechanism of the type referred to, comprising means for actuating a related instrumentality a predetermined number of times during a given period and including control means for regulating the number of actuations of such part during a given period, by the operation of which control means the number of actuations of such part during a given period may be increased or decreased, as desired, to suit conditions.

Another object of the invention is to provide trip mechanism for co-action with the vanes of the timing gear, comprising novel means for preventing injury to either the timing gear or trip mechanism resulting from varying the position of the latter during rotation of said gear.

Another object of the invention is the provision of quick-acting switch means for energizing the solenoid upon actuation of the trip mechanism.

While the timing mechanism of the present invention has been particularly designed for use in connection with apparatus of the type described in my co-pending application, above identified, said timing mechanism has application to a wide variety of uses and various types of apparatus as will readily appear to those skilled in the art.

My co-pending application, above identified, is, however, referred to by way of example of the manner in which the timing mechanism of the instant application may be employed for one of the uses to which it is suited.

In carrying my invention into practice, in one embodiment of the invention, the same comprises a timing gear provided with peripheral vanes of graduated axial lengths, trip mechanism designed to co-act with such vanes, switch means associated with said trip mechanism, and control means for shifting the position of the trip mechanism to position the same for co-ac-

tion with a particular desired number of the vanes provided on the timing gear.

An embodiment of the invention, comprising the structure just generally above mentioned, is more particularly described in the annexed specification and shown in the accompanying drawings, in which:

Figure 1 is a side view of apparatus embodying the invention, parts of the same being shown in section.

Figure 2 is a horizontal sectional view taken on the line 2—2 of Figure 1, looking in the direction of the arrows.

Figure 3 is a transverse vertical sectional view of the instrumentalities shown in Figure 1.

Figure 4 is an end view of the device showing more particularly the control instrumentalities.

Figure 5 is a wiring diagram showing the switch means of the invention in relation to a part actuated thereby and a source of power for operation of such part.

Now referring to the drawings for a detailed description of the invention, as seen best in Figure 2, a shaft 1 is provided at one end with a pinion 2 meshing with a timing gear 3. The timing gear 3 is journaled on a stub shaft 4, secured to a housing 5. The timing gear 3 is provided with a plurality of vanes 1a, 1b, 1c, 1d, 1e, 1f, 1g and 1h extending from the periphery of the timing gear. These vanes are of graduated axial lengths ranging from shortest to longest in the order named for a purpose to be hereinafter pointed out.

The number of vanes which will preferably be provided on the timing gear will be determined by the ratio of the pinion 2 to the gear 3, since the vanes are equidistantly spaced from each other on the periphery of the gear and the distance between them is the length of the arc of movement of the gear 3 during a complete revolution of the pinion 2.

In the embodiment of the invention shown, there are provided trip instrumentalities designed to co-act with one or more of the vanes 1 for actuating switch means cooperating with said trip instrumentalities. There is also provided control means for moving the trip instrumentalities axially respecting the timing gear to position said instrumentalities for co-action with a predetermined desired number of the vanes 1.

In the embodiment of the invention shown, the ratio of the pinion 2 to the timing gear 3 is one to eight, and, consequently, there are provided on the periphery of said gear eight equi-

distantly spaced vanes 7. Hence, if the trip instrumentalities are positioned for engagement with all of the vanes 7 of the timing gear 3 during a complete revolution of the latter, the switch cooperating with said trip instrumentalities will be actuated once during each complete revolution of the pinion.

As mentioned above, the vanes 7 are of different axial lengths and the trip instrumentalities are movable axially respecting the timing gear 3 so as to engage any desired number of vanes 7 from none to eight.

The timing gear 3 is positioned on the shaft 4 by a suitable lock nut 8 and washer 9. Pivotally mounted on an extension 4a of the shaft 4 is a balance bar 10 which is axially positioned respecting the said shaft by the shoulder 4b bearing against one edge of said bar 10 and a sleeve 11 bearing against the opposite edge of said bar. A mercury switch 12, secured between the clamping portions 13 of a bracket 14, is rockably mounted upon the shaft 4a, the bracket 14 comprising depending legs 14a and 14b journaled upon the sleeve 11 and the shoulder portion 4b.

The trip instrumentalities, which co-act with the timing gear vanes to cause actuation of the switch means above mentioned, will now be described.

A rock shaft 15 is pivotally connected to the balance bar 10, as at 15a, and secured to the rock shaft 15 is a link 16 pivoted, as at 17, to a crank 18a of a crank shaft 18, journaled in bearings 5a and 5b of the casing 5. Mounted for sliding movement along the crank shaft 18 is a forked trip member 19 which is adapted to be oscillated upon a corresponding movement of the crank shaft 18. For this purpose the crank shaft 18 is preferably rectangular in cross section, except at its ends which are rotatably journaled in the casing, and the trip member 19 is provided with a corresponding rectangular opening 19a for cooperation with said shaft. The trip member 19 comprises a pivoted trigger portion 19b pivoted to the trip member, as at 19c, and comprising a lever extension 19d to which is secured one end of a spring 20, the other end of said spring being secured to the trip member 19, as at 21.

The trigger 19b is thus normally positioned, as shown by the solid lines in Figure 3, with the lever extension 19d in abutment with the hub portion 19e of said trip member.

Control means, now to be described, are provided for shifting the trip member 19 axially respecting the timing gear 3, to position the trip member for co-action with a pre-determined number of the vanes 7 on said gear. A lever 22 for moving the trip member 19 axially respecting the crank shaft 18 is journaled upon the inner end of a stub shaft 23, secured to the casing 5, and comprises a rod 24 extending between the bifurcations 19f and 19g of the trip member 19.

Formed integral with the base or hub portion 22a of the lever 22 is a gear segment 22b meshing with a pinion 25a fixed to the inner end of a lever 25 journaled in the housing 5. The diameter of the pinion 25a is proportionately less than the diameter of the gear segment 22b so that a given arc of movement of the lever 25 will induce a proportionately smaller arc of movement of the lever 22, the ratio of the pinion 25a to gear segment 22b being, in the present instance, one to three.

The handle portion 25b of the lever 25 is provided with a plunger 25c normally pressed in-

wardly toward the casing 5 by a spring 25d bearing against the enlarged end 25e of said plunger. A handle 25f is provided for withdrawing the plunger against the compression of the spring. The pointed inner end 25g of the plunger is adapted to engage one or the other of a plurality of recesses 26 in the casing 5, designated by corresponding number indicia 27 on said casing, as shown in Figure 4. The number indicia 27, related to respective recesses 26, indicate corresponding positions of the levers 25 and 22 such that when the pointed end 25g of the plunger 25 is engaged in a particular one of said recesses 26, the trip member 19 will be positioned for engagement with a given number of the vanes 7, determining the number of times the trip instrumentalities will be actuated during a revolution of the timing gear.

The mercury switch 12 comprises the usual glass tube 12a containing mercury 12b from which tube terminals 28 and 28a lead respectively to the solenoid 30 and the power lines 29 to which are inter-connected the motor 31 for driving the shaft 1, the starter 32 for said motor, and the limit control switch 33 for said starter.

When the trip member 19 is in such a position axially respecting the rock shaft 15 as to permit engagement of one or more of the vanes 7a, 7b, 7c, 7d, 7e, 7f, 7g or 7h with the trigger 19b, each engagement of one of said vanes with said trigger will cause the trip member 19 to be moved in the direction of the dotted line position thereof, shown in Figure 1, resulting in corresponding rocking movement of the crank shaft 18 and crank 18a acting to draw upwardly the link 16 and consequently the balance bar 10, which, under such condition, engages the bracket 14 to cause the same to be rocked in a counterclockwise direction respecting the shaft 4a causing the mercury 12b to flow in a leftward direction in the tube 12a, respecting Figure 1, so that the mercury completes a circuit through the terminals 28 and 28a, as indicated in Figure 5. Completion of this circuit energizes the solenoid 30.

It will be noted that the number indicia 27 ranging from "0" to "8," corresponding to respective recesses 26 in Figure 4, are in reverse order from the order in which they appear in Figure 8 of my co-pending parent application, above identified. The reason for this is that in the instant case the number indicia 27, opposite which the control handle 25f is positioned, designates the number of times that the trip member 19 is engaged by a vane or vanes 7 during a complete revolution of the timing gear 3, while in the parent application, on the other hand, the particular number indicia 54, opposite which the control handle 52f is set, indicates the rate of fuel feed by reference to the number of times the ram is connected with the crank during a complete revolution of the timing gear.

The rightward axial extremities of the vanes 7 are in a common vertical plane, having reference to Figure 3, but, as above mentioned, said vanes are of graduated axial lengths ranging from the length of the vane 7a, which is the shortest, to that of vane 7h, which is the longest. Each of the other vanes is of a different axial length intermediate the lengths of the vanes 7a and 7h. Thus when the trip member 19 is positioned at its rightward extremity of axial movement, having reference to Figure 3, said member will be engaged by all of the vanes 7 during a complete revolution of the gear 3 and as said

member is progressively moved in a leftward direction to various positions indicated by the number indicia 27, it will be positioned for engagement with a less number of said vanes corresponding to the numerical position of the control handle 52f. Said vanes range in order of their length from shortest to longest in the following order: 7a, 7b, 7c, 7d, 7e, 7f, 7g and 7h. Upon reference to Figure 1, it will be noticed, however, that this order of the range of the length of said vanes does not follow the order of their proximity to one another. For example, vane 7b, which is next in length to 7a, is diametrically opposite the latter. Vane 7c, which is next in length to 7b, is not immediately proximate, vane 7e intervening. Vane 7d, which is next in length to vane 7c is again diametrically opposite the latter. Vane 7e, which is next in length to vane 7d, is substantially opposite the latter, while vane 7f is again diametrically opposite 7e, and vanes 7g and 7h, the former being the next in length to the latter, which is the longest, are also diametrically opposite.

The reason for the arrangement of the vanes as just described is to space the respective actuations of the switch 12 as nearly as possible at equal intervals throughout a given period such as that defined by a complete revolution of the timing gear 3.

The range of possible variations in number of actuations of the switch 12 during a given period is determined by the number of vanes with which the timing gear is provided. In the present instance the timing gear is provided with eight vanes so that it is possible to secure a variation from zero to eight in the number of actuations of the switch 12 during the pre-determined period required for a complete revolution of the timing gear.

Operation

We will assume that the control lever 25 is in its zero position with the pointed inner end 25g of the plunger 25c engaging in the recess 26 designated by the numeral "0." The trip member 19 will, therefore, be positioned in the dotted line position of Figure 3, that is, with the trigger portion 19b out of engagement with any of the vanes 7 of the gear 3. We will also assume that the shaft 1 and pinion 2 are rotating at a constant speed in a direction to cause clockwise rotation of the gear 3, having reference to Figure 1, and that it is desired to energize the solenoid 30 once during every eight revolutions of the pinion 2.

To accomplish this, the control lever 25 will be moved in a leftward direction, having reference to Figure 4, so that the pointed end 25g of the plunger 25c will be engaged in the recess 26, designated by the numeral "1" of the number indicia 27. Under such condition, the trip member 19 will have been moved, through the cooperation of pinion 25a and gear segment 22b for actuation of lever 22, in a rightward direction, having reference to Figure 3, from its dotted line position there shown, to a position in which the trigger portion 19b will be engaged by one only of the vanes 7, the same being the vane of greatest axial length, namely vane 7h.

With the trip member 19 in the position just described, the trigger 19b will be engaged by the vane 7h once during each revolution of the gear 3, and, since the ratio of the pinion 2 and the gear 3 is one to eight, the said trip member will be caused to rock to the dotted line position of

Figure 1 once during every eight revolutions of the pinion 2. As previously described, this rocking movement of the trip member 19 and its associated crank shaft 18 will, through the crank 18a and link 16, cause the balance bar 10 and the mercury switch 12 to be rocked in a counter-clockwise direction, having reference to Figure 1, causing the mercury 12b to flow in a leftward direction in the tube 12a so that the mercury completes a circuit through the terminals 28 and 28a, as indicated in Figure 5, to energize the solenoid 30.

Continued rotation of the gear 3 moves the co-acting vane 7h out of engagement with the trigger 19b after the trip member has reached the limit of its rocking movement, as shown by the dotted line position in Figure 1, whereupon the weight of balance bar 10 will cause the latter to move in a clockwise direction, having reference to Figure 1, to restore the mercury switch 12 and the trip member 19 to their normal positions indicated by solid lines in Figure 1.

Now, assuming that it is desired to energize the solenoid 30 five times during each eight revolutions of the pinion 2. The control instrumentalities will be correspondingly moved to a position in which the control handle 25f registers with the numeral "5" of the number indicia 27. In this position the trip instrumentalities will have been axially moved respecting the timing gear 3 so that the trigger portion 19b of the trip member 19 will be engaged by five of the vanes 7 during each revolution of the gear 3. The vanes 7 which will co-act with the trigger portion when the trip member is in this position will, of course, be the five vanes of greatest axial length, the same being 7h, 7g, 7f, 7e and 7d.

While the vanes just enumerated are not spaced at identically equal intervals on the periphery of the timing gear 3, they are, nevertheless, spaced at intervals as nearly as possible spread out on the periphery of said timing gear in view of the fact all positions of adjustment of the trip member also make desirable as nearly as possible equal spacing of the vanes to be engaged during a revolution of the timing gear. Consequently, when the trip member 19 is in its position No. "5," just described, the solenoid 30 will be energized in the manner before described five times during each eight revolutions of the pinion 2, and the times of energization will be spaced as nearly as possible at equal intervals throughout the period required for said pinion to make eight revolutions.

The foregoing will be understood to be true as well in reference to all other settings of the control handle 25f, that is, that the times of co-action of a particular number of vanes 7 with the trip member 19, and, consequently the times of actuation of the switch means 12, will be spaced at fairly equal intervals throughout the period required for eight revolutions of the pinion 2 in respect to each setting of the control handle 52f.

It will be noticed that the relation of the trigger 19d to the trip member 19 is such that the latter may be shifted axially respecting the crank shaft 18 regardless of the position of rotation of the timing gear 3. Should the trip member 19 happen to be moved rightwardly, referring to Figure 3, from the dotted line position, indicated in Figure 3, at a time when such axial shifting of the trip member would cause the trigger 19b to engage the outer edge of one of the vanes on the timing gear 3, the trigger 19b would simply

be caused to move about its pivot 19c to the angular dotted line position of Figure 3, during such axial shifting of the trip member 19, without injury thereto.

Further rotation of the timing gear 3, moving the vane so engaged out of contact with the trigger 19b, will result in restoration of the vertical position of the trigger 19b by action of the spring 28.

Upon reference to Figures 1 and 3 it will be noticed that the bracket 14 is spaced somewhat from the upper edge of the balance bar 10 resulting in a certain amount of play between the bracket and said bar. This provision has the following result. The flow of mercury 12b in the tube 12 lags somewhat behind the speed of flow which would normally result from the angular movement of the bar 10 if the bracket and bar were integral. At the moment the mercury overbalances the bracket 14 in the direction of the terminals 28 and 28a, however, said bracket moves with greater rapidity toward the limit of its overbalanced position in that direction, as defined by the abutment of said bracket with said bar. Furthermore, when the tube 12 is returned toward normal position by the balance bar after an engaging vane passes out of co-action with the trip member 19, the flow of mercury in said tube lags again, resulting in maintaining the solenoid 30 energized longer than would otherwise be the case.

Having thus described my invention, what I claim as new and desire to secure by Letters Patent of the United States is:

1. In a device of the class described, in combination, a timing member including spaced trip engaging elements, trip instrumentalities operable upon engagement with said elements during movement of said member, said instrumentalities being movable relative to said member to position said instrumentalities for engagement with pre-selected ones of said elements, said instrumentalities including a trip member comprising parts pivoted to swing integrally in one plane respecting said timing member upon actuating engagement of said elements therewith, one of said parts being pivotally movable relative to the other part in another plane upon engagement of one of said elements therewith during positioning movement of said instrumentalities relative to said timing member, and means yieldably resisting pivotal movement of said one part respecting said other part.

2. In a device of the class described, in combination, a timing member including spaced trip engaging elements, a trip member operable upon engagement with said elements during movement of said timing member, a pivoted supporting bar therefor, said trip member being longitudinally movable relative to said bar to position said trip member for engagement with pre-selected ones of said elements, said trip member being connected to said bar for transmission of angular movement of said trip member to said bar, and switch means associated with said bar for actuation thereby upon angular movement of said trip member.

3. In a device of the class described, in combination, a timing member including spaced trip engaging elements, a trip member operable upon engagement with said elements during movement of said timing member, a pivoted supporting bar therefor, said trip member being longitudinally movable relative to said bar to position said trip member for engagement with pre-selected ones

of said elements, said trip member being connected to said bar for transmission of angular movement of said trip member to said bar, and switch means associated with said bar for actuation thereby upon angular movement of said trip member, said trip member including a fork, and control means for positioning the trip for engagement with the desired number of said elements including a pivoted lever having a part

engaging said fork.

4. In a device of the class described, in combination, a rotatable timing member having circular periphery, a plurality of equally spaced vanes extending therefrom, said vanes being pro-

gressively graduated in respect to their axial lengths and each having a different axial length, a trip member operable upon engagement with said vanes during rotation of said timing member, a pivoted supporting bar for said trip mem-

ber, said trip member being longitudinally movable relative to said bar to position said trip member axially respecting said timing member for engagement with preselected ones of said vanes, those vanes next in the progression of their axial lengths being arranged on the periph-

ery of the timing member in such a manner that when the trip member is positioned for actuation by any desired number of said vanes, the actuations will be spaced as nearly as possible at equal intervals throughout the cycle of a complete revolution of the timing member.

5. In a device of the class described, in combination, a rotatable timing member having circular periphery, a plurality of equally spaced vanes extending therefrom, said vanes being pro-

gressively graduated in respect to their axial lengths and each having a different axial length, a trip member operable upon engagement with said vanes during rotation of said timing member, a pivoted supporting bar for said trip member, said trip member being longitudinally movable relative to said bar to position said trip member axially respecting said timing member for engagement with preselected ones of said vanes, those vanes next in the progression of their axial lengths being arranged on the periph-

ery of the timing member in such a manner that when the trip member is positioned for actuation by any desired number of said vanes, the actuations will be spaced as nearly as possible at equal intervals throughout the cycle of a complete revolution of the timing member, said trip member being connected to said bar for trans-

mission of angular movement of said trip member to said bar, and switch operating means asso-

ciated with said bar for actuation thereby upon angular movement of said trip member.

6. In a device of the class described, in combination, a timing member including spaced trip engaging elements, a trip member operable upon engagement with said elements during move-

ment of said timing member, a pivoted sup-

porting bar therefor, said trip member being longitudinally movable relative to said bar to position said trip member for engagement with pre-

ing positioning movement of said trip member, and means for restoring the normal relation of said parts.

7. In a device of the class described, in combination, a timing member including spaced trip engaging elements, a trip member operable upon engagement with said elements during movement of said timing member, a pivoted supporting bar therefor, said trip member being longitudinally movable relative to said bar to position said trip member for engagement with pre-selected ones of said elements, said trip member being connected to said bar for transmission of angular movement of said trip member to said bar, a pivoted switch member, and means operable upon angular movement of said bar for pivoting said switch member to contacting position.

8. In a device of the class described, in combination, a timing member, trip instrumentalities periodically operable thereby, and switch means operable by said trip instrumentalities, said switch means comprising a mercury switch, a loosely pivoted bracket carrying the same, a balance bar pivoted on the axis of said bracket and engaging the same in either contacting or non-contacting position of the switch and normally maintaining the same in the latter position, the bracket and balance bar being so

mounted as to permit relative movement therebetween, and means operable by said trip instrumentalities for moving said switch to contacting position.

5 9. In a device of the class described, in combination, a timing member including spaced trip engaging elements, a trip member operable upon engagement with said elements during movement of said timing member, a pivoted supporting bar therefor, said trip member being longitudinally movable relative to said bar to position said trip member for engagement with pre-selected ones of said elements, said trip member being connected to said bar for transmission of angular movement of said trip member to said bar, a pivoted switch member, a balance bar pivoted on the axis of said switch member and engaging the same in either contacting or non-contacting position of the switch and normally maintaining the same in the latter position, a crank on the pivoted bar, and means interconnecting the crank and the balance bar for moving the switch to contacting position upon angular movement of the pivoted bar, the switch and balance bar being so mounted as to permit relative movement therebetween.

WALTER J. HAAG.
